UNITED STATES PATENT OFFICE.

ANGELO CENTONI, OF CHICAGO, ILLINOIS.

CONTROLLER FOR ELECTRIC SIGNS.

Application filed March 25, 1922. Serial No. 546,712.

To all whom it may concern:

Be it known that I, ANGELO CENTONI, a citizen of the United States of America, and a resident of Chicago, in the county of Cook and State of Illinois, have invented certain Improvements in Controllers for Electric Signs, of which the following is a specification.

This invention relates to that class of changeable electric signs in which the display field of the sign is provided with a plurality of closely arranged electric lamps, the individual circuits of which extend to a remote switch board or station where circuits of groups of said lamps forming the desired letter or symbol are automatically closed and the illumination of the same attained by a series of pattern plates carried by a travelling carrier, with such pattern plates having the required surface formation to simultaneously close the circuits of the lamps forming the desired letter or symbol. And the present improvement has for its objects:

23 To provide a structural formation and association of parts and circuits, wherein a primary opening or breaking is effected in the main supply circuit, and from which individual circuits and circuit closers of the display field lamps are supplied, previous to a movement of the operating mechanism by which a shifting of the pattern plates is effected, with an entire avoidance of the injurious sparking at the aforesaid individual circuit closers, with a confinement of the sparking action to the main switch, in which convenient means can be provided to dampen and withstand the sparking effect.

To provide a construction of travelling carrier of a sectional form, in which the adjacent ends of the sections are connected together in a hinged and disconnectable manner to provide for ready removal and replacement, with each section having holding means for a pattern plate formed to close the circuits of a predetermined cluster of lamps in the display field of the sign and produce the desired letter or symbol in such field.

50 To provide a simple and efficient formation of the replaceable pattern plates in an economical manner, all as will hereinafter more fully appear.

In the accompanying drawings—

55 Fig. 1, is a side elevation with parts broken away, of an electric sign controlling

mechanism embodying the present invention.

Fig. 2, is a front end elevation of the mechanism.

60 Fig. 3, is an enlarged detail longitudinal section on line 3—3, Fig. 2, the circuit connections of the apparatus being shown in diagram.

Fig. 4, is an enlarged detail horizontal section on line 4—4, Fig. 3.

Fig. 5, is an enlarged detail longitudinal section on line 5—5, Fig. 6.

Fig. 6, is an enlarged detail transverse section on line 6—6, Fig. 3.

70 Fig. 7, is a detail side elevation of the endless carrier with the pattern plates in position.

Fig. 8, is a bottom plan of same.

Like reference numerals indicate like 75 parts in the several views.

Referring to the drawings, 1 designates the supporting base provided with uprights or standards 2 and 3, the forward upright 2 of which is fixed on the base 1, while the 80 rear upright 3 is connected to the base 1 in a longitudinally adjustable manner by guideways or rods 4 on said base, with a view to the proper tensioning of the travelling endless carrier of the machine, as well 85 as provide for different lengths in said carrier as circumstances may indicate and as usual in the present class of mechanisms.

5 and 6 designate transverse shafts journaled in the upper ends of the standards 90 2, 3, and carrying drums 7 and 8 for the support of the endless pattern carrier hereinafter described.

9 designates a ratchet wheel fixed on the shaft 5 and forming an element of the actuating mechanisms by which intermittent travel is imparted to the drum 7 and the endless carrier thereon.

10 designates a transverse countershaft journaled on the standards 2 in spaced relation to the drum shaft 5, and receiving constant rotation through a reducing gear connection 11 from an electric or like motor 12 mounted on the base 1, as shown.

13 designates a cam or wiper fixed on and revolving with the counter-shaft 10 and adapted for operative engagement with a head or bar 14 moving in vertical guides on the standards 2 aforesaid, to impart intermittent reciprocation to said head or bar.

15 designates a pawl preferably of the weighted type, pivoted at the upper end of

- bar or head 14 and adapted for engagement with the ratchet wheel 9 aforesaid, to impart the required intermittent rotation to the same.
- 5 16 designates the stationary member, and 17 the movable member of a switch of any usual construction, arranged in the main supply line 18 of the apparatus, and in advance of the plurality of individual wires 10 which extend through a corresponding plurality of individual switches, to the plurality of electric lamps in the display field of the sign, hereinafter described in detail.
- 19 designates a connecting rod or link between the aforesaid head or bar 14 and the movable member 17 of the switch, and adapted to open the circuit of said switch at the commencement of the upward movement of the head or bar 14, to shut off or break
- 15 20 the electric supply to the aforesaid individual switches, previous to and during the shifting of a pattern plate out of operative position and its replacement by a succeeding pattern plate.
- 20 25 30 35 40 45 50 55 60 65 70 75 80 85 90 95 100 105 110 115 120 125 130
- 29 designates a live wire connection between the guide head 26 and the outflow end of the main switch above described.
- 30 designate a series of rectangular frames flexibly connected together by open pivot eyes 31 and hooks 32 on their respective ends, so as to be capable of ready assemblage, disassemblage and replacement. With a series of said frames connected together in an endless manner and mounted on the drums 7 and 8 they constitute the endless pattern carrier of the present construction.
- 33 designate undercut holding lugs arranged near the opposite end margins of the aforesaid frames 30 and adapted for holding engagement with pattern plates hereinafter described, after such plates have been slipped endwise into the holding channels of said ears.
- 34 designates a stop lug at the remote side of each frame 30 and adapted to stop and properly position a pattern plate when the same is slipped into holding engagement with the lugs 33 aforesaid.
- 35 designate the series of pattern plates heretofore referred to, of a rectangular form and each comprising a flat plate of metal or like conducting material, the inner portion 36 of which is embossed with the desired letter, symbol or character which it is intended to reproduce in the display field of the sign, with the plane edges of the plate adapted to have free sliding movement into place in the channels of the holding lugs 33, aforesaid.
- In the described construction and arrangement of parts, the main portion of a pattern plate 35 moves in a plane above and out of contact with the contact points or pins 21 heretofore described, while the depending or downwardly embossed letter or symbol portions of the pattern plate moves in a plane in line with said contact points or pins 21 and completes the individual circuits between the source of electric supply and the lamps in the display field of the sign, and establish an illuminated letter, symbol or character in said field corresponding with the form or configuration of the depending portion or portions of the pattern plate.
- The electro-motive force passing along the supply and return lines 18, 18' as shown in Fig. 3, is controlled by a switch 18'' as usual. The supply line 18 extends to the motor 12 and has a branch line extending to the automatically operated switch 17 heretofore described, and from thence by a line 29 to the cross head 26 of conducting material, and which in turn has electric contact with the pattern plates 35 also of conducting material. With the described construction, the pattern plate 35 in superimposed relation to the bed plate 20, of the apparatus, has electrical contact with the series of individual insulated contact points 21 that are in the

zone of the symbol 36 on said pattern plate 35, and in that the entire series of contact points 21 have the usual individual connection with similarly arranged lamps in the display field 37, an illuminated representation of said symbol is produced in said display field.

Having thus fully described my invention, what I claim as new and desire to secure by Letters Patent, is:—

1. In a changeable electric sign of the type described, the combination of side standards, a cross head fixed on said standards and provided with longitudinal side flanges, a travelling carrier having guiding engagement with said flanges, pattern plates of conducting material mounted on said carrier and formed with downwardly projecting portions having symbol form, means for connecting said pattern plates with an electric source, a transverse bed fixed on the aforesaid standards in spaced relation beneath said cross head, a plurality of contact points carried in insulated relation to each other on said bed and having individual line connections extending to individual lamps in the display field of an electric sign, said contact points being arranged in the path of the depending portions of the pattern plates and adapted for electric contact therewith in a super-imposed relation of a pattern plate, and means for imparting intermittent travel to said carrier.

2. In a changeable electric sign of the type described, the combination of side standards, a cross head of conducting material fixed on said standards and provided with longitudinal flanges at its sides, an electric supply line connected to said cross head, a travelling carrier having guiding engagement with said flanges, pattern plates mounted on said carrier and formed downwardly projecting portions having a symbol form, said carrier and pattern plates being formed of conducting material; a transverse bed of non-conducting material fixed on said standards in spaced relation beneath said cross head, a plurality of contact points mounted in close insulated relation on said bed and having individual line connections extending to individual lamps in the display field of an electric sign, said contact points being arranged in the path of the depending portions of the pattern plates and adapted for electric contact therewith, and means for imparting intermittent travel to said carrier.

60 3. In a changeable electric sign of the type described, the combination of side standards, a cross head fixed on said standards and provided with longitudinal side flanges, a travelling carrier having guiding engagement with said flanges, pattern plates of conducting material mounted on said carrier and formed with downwardly projecting portions having symbol form, means

65

for connecting said pattern plates with an electric source, a transverse bed fixed on the aforesaid standards in spaced relation beneath said cross head, a plurality of contact points carried in insulated relation to each other on said bed and having individual line connections extending to individual lamps in the display field of an electric sign, said contact points being arranged in the path of the depending portions of the pattern plates and adapted for electric contact therewith in a superimposed relation of a pattern plate, and means for imparting intermittent travel to said carrier, a switch arranged in the electric line connection of the pattern plates, and operating connections between the movable element of said switch and the means for imparting travel to the carrier.

4. In a changeable electric sign of the type described, the combination of side standards, a cross head fixed on said standards and provided with longitudinal side flanges, a travelling carrier having guiding engagement with said flanges, pattern plates of conducting material mounted on said carrier and formed with downwardly projecting portions having symbol form, means for connecting said pattern plates with an electric source, a transverse bed fixed on the aforesaid standards in spaced relation beneath said cross head, a plurality of contact points carried in insulated relation to each other on said bed and having individual line connections extending to individual lamps in the display field of an electric sign, said contact points being arranged in the path of the depending portions of the pattern plates and adapted for electric contact therewith in a superimposed relation of a pattern plate, and means for imparting intermittent travel to said carrier, a drum mounted on said standards and forming a partial support for said carrier, a ratchet wheel and operating pawl associated with said drum, power driven means for imparting oscillation to said pawl, a switch arranged in the electric line connection of the pattern plates, and operative connections between the movable element of said switch and the operative connections of said pawl. 115

5. In a changeable electric sign of the type described, the combination of side standards, a cross head of conducting material fixed on said standards and provided with longitudinal flanges at its sides, an electric supply line connected to said cross head, a travelling carrier having guiding engagement with said flanges, pattern plates mounted on said carrier and formed with downwardly projecting portions having a symbol form, said carrier and pattern plates being formed of conducting material, a transverse bed of non-conducting material fixed on said standards in spaced relation beneath said cross head, a plurality of contact points 130

mounted in close insulated relation on said bed and having individual line connections extending to individual lamps in the display field of an electric sign, said contact points being arranged in the path of the depending portions of the pattern plates and adapted for electric contact therewith, and means for imparting intermittent travel to said carrier, a switch arranged in the electric line connection to the cross head aforesaid, and operative connections between the movable element of said switch and the means for imparting travel to the carrier.

6. In a changeable electric sign of the type described, the combination of side standards, a cross head of conducting material fixed on said standards and provided with longitudinal flanges at its sides, an electric supply line connected to said cross head, a travelling carrier having guiding engagement with said flanges, pattern plates mounted on said carrier and formed with downwardly projecting portions having a symbol form, said carrier and pattern plates being formed of conducting material, a transverse bed of conducting material fixed on said standards in spaced relation beneath said cross head, a plurality of contact points mounted in close insulated relation on said bed and having individual line connections extending to individual lamps in the display field of an electric sign, said contact points being arranged in the path of the depending portions of the pattern plates and adapted for electric contact therewith, and means for imparting intermittent travel to said carrier, a drum mounted on said standards and forming a partial support for said carrier, a ratchet wheel and operating pawl associated with said drum, power shaft mounted on said standards, a cam on said shaft, a sliding head intermediate of said cam and the aforesaid pawl, a switch arranged in the electric line connection of the pattern plates, and a rod connection between said sliding head and the said pawl.

7. In a changeable electric sign of the type described, the combination of side standards, a cross head fixed on said standards and provided with longitudinal side flanges, a travelling carrier having guiding engagement with said flanges, pattern plates of conducting material mounted on said carrier and formed with downwardly projecting portions having symbol form, means for connecting said pattern plates with an electric source, a transverse bed fixed on the aforesaid stand-

ards in spaced relation beneath said cross head, a plurality of contact points carried in insulated relation to each other on said bed and having individual line connections extending to individual lamps in the display field of an electric sign, said contact points being arranged in the path of the depending portions of the pattern plates and adapted for electric contact therewith in a superimposed relation of a pattern plate, and means for imparting intermittent travel to said carrier, a drum mounted on said standards and forming a partial support for said carrier, a ratchet wheel and operating pawl associated with said drum, a power shaft mounted on said standards, a cam on said shaft, a sliding head intermediate of said cam and the aforesaid pawl, a switch arranged in the electric line connection of the pattern plates, and a rod connection between said sliding head and the said pawl.

8. In a changeable electric sign of the type described, the combination of side standards, a cross head of conducting material fixed on said standards and provided with longitudinal flanges at its sides, an electric supply line connected to said cross head, a travelling carrier having guiding engagement with said flanges, pattern plates mounted on said carrier and formed with downwardly projecting portions having a symbol form, said carrier and pattern plates being formed of conducting material, a transverse bed of non-conducting material fixed on said standards in spaced relation beneath said cross head, a plurality of contact points mounted in close insulated relation on said bed and having individual line connections extending to individual lamps in the display field of an electric sign, said contact points being arranged in the path of the depending portions of the pattern plates and adapted for electric contact therewith, and means for imparting intermittent travel to said carrier, a drum mounted on said standards and forming a partial support for said carrier, a ratchet wheel and operating pawl associated with said drum, power driven means for imparting oscillation to said pawl, a switch arranged in the electric line connection of the pattern plates, and operative connections between the movable element of said switch and the operative connections of said pawl.

9. In a changeable electric sign of the type described, the combination of side standards, a cross head fixed on said standards and provided with longitudinal side flanges, a travelling carrier having guiding engagement with said flanges, pattern plates of conducting material mounted on said carrier and formed with downwardly projecting portions having symbol form, means for connecting said pattern plates with an electric source, a transverse bed fixed on the aforesaid stand-

Signed at Chicago, Illinois, this 23rd day of March 1922.

ANGELO CENTONI.
